JOSEPH F. D. HOGE, OF NEW YORK, N. Y.

THERMOSTAT.

1,329,122.

Specification of Letters Patent. Patented Jan. 27, 1920.

Application filed September 18, 1916. Serial No. 120,642.

To all whom it may concern:

Be it known that I, JOSEPH F. D. HOGE, a citizen of the United States of America, and a resident of New York, county of New York, and State of New York, have invented 5 certain new and useful Improvements in Thermostats, of which the following is a specification.

My invention relates to thermally-actuated circuit-breaking devices of the type 10 commonly termed thermostats, and comprises means whereby thermostats are rendered very rapid in operation, and yet are simple, inexpensive, free from liability to 15 mechanical injury, and very reliable.

The objects of my invention are to increase the rapidity or responsiveness of thermostats; to produce a thermostat which shall be more reliable or certain in its action than 20 former thermostats and to so construct the thermostat that it shall be very durable, free from liability to breakage in handling, packing, shipping, erection, etc., and which shall be simple and inexpensive to construct, 25 and positive in its action.

I will now proceed to describe my invention with reference to the accompanying drawings, and will then point out the novel features in claims.

30 In said drawings:

Figure 1 shows a side elevation of one form of thermostat embodying my invention.

Fig. 2 a bottom view thereof, and

35 Fig. 3 a transverse section thereof on the line 3—3 of Fig. 2.

My improved thermostat is of the type 40 wherein, in the event of the thermostat being heated above a predetermined degree, a weight member is released through the fusing of solder-joints and thereby a circuit is opened. The promptness of operation of such thermostats depends to a very large degree upon the mass of metal to be heated; 45 for if there be considerable metal to be heated, considerable time will elapse before the solder will be heated to the fusing point; for this solder heats no more rapidly than does the metal with which it is in contact 50 or in heat-conducting relation. According to the present invention I have reduced the mass of the metal to be heated, in order that the solder may melt, to a very low degree, by constructing the thermostat of two light 55 spring members, and a hollow shell, also of very thin metal, containing within it a heat

insulated weight mass, such shell being connected to the said springs by the low melting solder commonly employed in these thermostats. The springs are, of course, connected 60 to a suitable base, but this base is preferably made of material of low heat conductivity; and because of this fact, and because of the fact that the weight mass within the said shell is heat insulated, the only parts 65 to be heated, in addition to the solder, are, the said thin springs, and the said thin shell. This shell is of such construction as to present a very large relative surface area, thereby facilitating the absorption of heat by the 70 parts to be heated.

In the said drawings, 1 designates a base, preferably of material of low heat conductivity, such for example as fiber or porcelain; 2—2 designate the said springs, preferably 75 of the U-form shown, and 3 designates the said shell, preferably, though not necessarily, of approximate spherical form. The springs 2 and the shell 3 are connected by small solder-masses 4, the composition of the 80 solder being such as to cause it to melt at some desired and predetermined temperature.

The shell 3 is hollow, and contains within it a weight mass 5, surrounded by heat-insulating and cushioning material 6, such for example, as loose cotton or wool fiber, spun-glass fiber, mineral wool, asbestos, etc. This fibrous packing material is employed for two 85 principal purposes; viz., to reduce to a minimum conduction of heat from the shell 3 to said weight mass, and also to reduce the impact of said shell when, after detachment from the springs 2 it strikes some object in falling. While in general, it is not probable 90 that anything would be harmed by the fall upon it of the shell 3 with the weight mass inside, yet it might happen that this shell might fall upon crockery or something of the sort, and do injury thereto; unless the 95 fall be cushioned. Now it is clear that the mass of the shell 3 itself is so small that the shell itself is not apt to do injury when it strikes an object; the more so as the metal of this shell is very thin, so that if such 100 shell strikes a solid object with any considerable force, it will be apt to crush, so cushioning the impact. Of course the weight mass 5 falls with the shell; but because of the cushioning material 6, when the shell 105 strikes an object, the stoppage of the weight mass is retarded or cushioned, so greatly re-

ducing the impact of the blow. However, the principal reason for the employment of the cushioning material is to substantially eliminate the weight mass as a factor retarding the heating up of the shell, solder and springs.

The spherical form of the shell 3 is further desirable, since it substantially insures the operation of the thermostat, upon the 10 fusion of the solder, in whatever position the thermostat be placed. Preferably, of course, the thermostat is placed with its base up and shell 3 down, as indicated in Fig. 1; but the thermostat may be placed 15 in various other positions, for example, with its base inclined or vertical, and still, upon fusion of the solder, the shell 3 will fall away from the springs 2, so opening the circuit of which those springs form terminals.

Solder of low melting point, such as is employed in thermostats, though quite strong, is also brittle, and in the past, fusible joint thermostats have frequently been 25 rendered inoperative through breakage of a solder connection, due to careless handling or some mechanical injury received in erection, or otherwise. To reduce this liability to mechanical injury to a minimum, I preferably make the springs 2 of U-form, and so proportioned that the shell 3 is supported clear of the base 1. The springs being very 30 flexible, the shell 3 can yield in any direction to jar or vibration, to force applied 35 in handling, or to contact with tools during erection. It is thus possible to handle the thermostat without particular care, to ship it without careful packing, and to erect it without the exercise of special precautions 40 against breakage of the solder joints.

As will be apparent from the foregoing, normally there is a circuit path through the thermostat from the one spring 2 through the shell 3 to the other spring 2. 45 In case of a fire occurring within the vicinity of the thermostat, the solder masses 4 will melt, releasing the ball or shell 3, which will then drop clear of the springs 2, opening this said circuit.

Many prior thermostats have afforded undesirable refuges for insects; and it will be noticed that the design of my thermostat is such that it provides no such refuge. Many prior thermostats have been so constructed that paint or whitewash if carelessly applied to them, might interfere with their operation; but such is not the case 55 with my present thermostat. Furthermore, my thermostat is not dependent for its operation upon spring action; the springs 2 are mere supports for the weight 3, and in the event of the solder masses 4 melting, this weight 3 will drop clear of the springs 2, independent of any spring action. The

spring support of the weight 3, however, 6 renders the thermostat free from deterioration due to building vibration; for the springs substantially neutralize any effect of building vibration so far as the solder joints are concerned.

Furthermore, the thermostat may be inspected at a glance, before and after installation, and its readiness for operation determined immediately by even inexperienced persons. Also, there is no occasion 7 for adjustment of any parts after installation.

What I claim is:

1. A thermostat comprising a detachable member, supporting means therefor, comprising a fusible connection, and a weight mass carried by such detachable member but heat insulated therefrom.

2. A thermostat comprising a hollow container, a weight mass therein, heat insulating material surrounding said weight mass and insulating the same from said container, and a support for such container comprising a fusible joint.

3. A thermostat comprising in combination a closed hollow shell of thin material of high heat conductivity, a weight mass within such shell, heat insulating material surrounding such weight mass and insulating the same from said shell, and supporting means for said shell comprising a fusible joint.

4. A thermostat comprising a heat-absorbing member and a weight mass, the said heat absorbing member being of relatively 100 small mass and large surface area, the said weight mass being carried by such heat absorbing member, in such manner as to reduce largely transmission of heat from such heat absorbing member to such weight mass, 105 and a support for such heat absorbing member comprising a fusible joint.

5. A thermostat comprising in combination a weight, two U-springs supporting that weight, and fusible joints connecting 110 such U-springs to said weight.

6. A thermostat comprising in combination a separable heat absorbing member consisting of a hollow shell of thin material of high heat conductivity, and supporting 115 means for said shell comprising a fusible joint, said shell arranged to fall away upon the fusion of such joint, the construction being such that because of the thinness of such shell and its large surface area, such 120 shell will heat rapidly.

In testimony whereof I have signed this specification in the presence of two subscribing witnesses.
